UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,242,085.

Specification of Letters Patent.

Patented Oct. 2, 1917.

Application filed April 13, 1917. Serial No. 161,854.

To all whom it may concern:

Be it known that I, HENRY G. VOIGHT, of New Britain, county of Hartford, and State of Connecticut, have invented certain new and useful Improvements in Locks, of which the following is a full, clear, and exact description.

This invention relates to locks, and it has special reference to locks for doors of hotel rooms which are lighted by electricity.

One of the objects of the invention is to provide improved means for switching off the light, or lights, automatically when the door is closed and locked from the outside, so that when the guests leave the room the lights cannot be left on, inadvertently, to waste the current.

To this and other ends the invention consists in the novel features and combinations of parts to be hereinafter described and claimed.

In the accompanying drawings,

Figure 1 is a front elevation of a mortise lock embodying my improvements, with the cap plate removed, the dead bolt mechanism being in the normal or retracted position.

Fig. 2, is a view of the upper part of the lock shown in Fig. 1, and of a part of the strike plate and light-controlling switch, showing the main deadbolt protracted by the thumb turn from the inside of the door.

Fig. 3 is a reverse sectional view of the upper part of the lock illustrating the parts in the positions shown in Fig. 2.

Fig. 4 is a front elevation of the upper part of the lock showing the bolt mechanism being protracted from the outside by the change key, with the light-controlling bolt head pressing back the switch plunger.

Fig. 5 shows how the deadbolt mechanism is retracted from the inside of the door, in case the door is inadvertently locked from the outside by the maid's key with the guest inside.

Fig. 6 is a section on line 6—6, Fig. 1.

Fig. 6^a is a similar section showing the main bolt protracted and the light-controlling bolt head retracted.

Fig. 7 is a fragmentary view of the front of the lock.

Fig. 8 is a detail section on line 8—8 of Fig. 7.

Fig. 9 is a detail, similar to Fig. 8, showing the parts in another position.

Figs. 10 and 11 are detail sections on lines 55 10—10, and 11—11, respectively, of Fig. 1.

Fig. 12 comprises details of the main bolt.

Fig. 13 is a detail of the auxiliary or light-controlling bolt head.

Figs. 14 and 15 are details of the connecting means for the bolt heads.

Fig. 16 comprises views of the change key and emergency key, respectively.

I have shown my improvements applied to a mortise lock having a single main locking bolt, which is protractable from the inside of the room by means of a thumb turn and from the outside by means of a cylinder lock having the usual series of keys customary in locks of the hotel type. The lock 70 also has a knob-controlled latchbolt. The particular features forming the subject of the present application may, however, be used to advantage in locks of other types, and, while my invention is particularly applicable to the control of a light-controlling switch for the purpose above pointed out, it is not wholly restricted or limited to such use or application.

In the particular form shown, the usual 80 mortise lock case 20 having the face plate 21 is equipped with a main deadbolt or locking bolt 22, operative from the outside of the room by means of a cylinder lock 23 having a series of keys. This locking bolt 85 is operative from the inside of the room by means of a thumb turn knob (not shown) engaging a thumb-turn hub 24 of ordinary type. Beneath the deadbolt, a latchbolt 25 is normally projected out of the face plate 90 by a spring 26, and is adapted to be retracted by knobs (not shown) connected in the usual way with a hub 27 actuating a retracting yoke or knob shoe 28.

The deadbolt 22 has a shank 29 guided by a slot 30 on the fence or stump 31 cast on the back of the case, and the shank of the bolt also has a slot 32, by means of which it clears the thumb-turn hub 24. Above the slot 32 the bolt is provided with a pair of 100 talons 33, adapted to be engaged by a cam or rollback 34 on the cylinder lock 23 previously mentioned. A primary tumbler 35 is pivoted on the bolt at 36 and bodily carried thereby. This tumbler has a lug 37 105 adapted to cooperate in the usual manner with the fence 31 so as to lock the bolt either in the projected position or the retracted

position. At the rear extremity of the tumbler 35, the same is provided with a loop 38 which embraces and clears the thumb turn hub 24, and on the upper part of the loop is 5 a projection 39 which lies between the talons 33 and is adapted to be engaged by the cam or rollback 34, previously mentioned, for the purpose of releasing the lug 37 from the fence 31 while the rollback in acting on 10 the talons projects or retracts the bolt in the usual manner.

Mounted below the deadbolt 22 is a slide 40 which is suitably guided for reciprocation in a line parallel to the deadbolt and 15 is adapted to protract said bolt through the actuation of the thumb-turn hub 24. In the form shown, the slide has a groove engaging a guide fin 41 on the back of the case, and a shoulder 42 projecting upwardly from 20 the slide engages a recess 43 on the lower edge of the bolt shank. When the parts are in the position shown in Fig. 1, the shoulder 42 engages the forward edge of recess 43 so that the bolt may be protracted by the 25 forward movement of the slide, as shown in Fig. 3. The slide carries a post 44 on which is pivoted a secondary tumbler 45 which is adapted to be actuated either by the thumb-turn hub 24, or by an auxiliary or emergency rollback 46, (Fig. 4) of the cylinder lock. For this purpose the secondary tumbler is provided with a pin 47 projecting over the loop 38, of the primary tumbler, and located between wings 24^a, 24^b, on the 30 hub 24 while an arm 46^a extends from the end of the secondary tumbler back against the rear wall of the case and upward into proximity to the cam or rollback 46, as shown at 46^b, so as to coöperate with said 35 rollback in depressing the secondary tumbler. It will be understood that the sweep portion 46^b of the secondary tumbler lies in the plane of the cam 46 of the cylinder lock, while the talons of the deadbolt and the 40 projection 39 of the primary tumbler lie in the plane of the cam 34. The cylinder lock construction is substantially the same as that shown in my application, Serial No. 95376, and it is therefore unnecessary to 45 describe it in detail. It may be said, however, that the cam 34 is fixed to a key plug which is rotatable by both the change key 48 and the emergency key 49 (Fig. 16), whereas the cam 46 is mounted on a short sleeve which 50 can be rotated only by the emergency key 49. In other words, the change key operates the primary cam alone, and the emergency key operates both cams simultaneously.

60 The secondary tumbler 45 coöperates with a fence 50 on the back of the case, which is adapted to hold said tumbler and thereby the connected slide 40 either in the retracted position or in the advanced position. A lug 65 51 on the intermediate portion of the sec-

ondary tumbler is located above the hook 52 depending from the primary tumbler, the arrangement being such that the depression of the secondary tumbler, either through the thumb-turn hub or through the cylinder lock mechanism, will cause a corresponding depression of the primary tumbler so as to disengage the same from the fence 31.

In the particular form shown, the head of the deadbolt 22 occupies the lower portion, 75 only, of the opening 53 in the face plate 21, as shown in Fig. 7. Above this deadbolt head in the opening 53 is the head of a subsidiary or auxiliary bolt 54 shown in detail in Fig. 13. The auxiliary bolt is adapted to 80 actuate any ordinary form of light-controlling switch 55 located behind the strike plate 56, as shown in Fig. 2, and having an operating plunger 57 located in the keeper opening of the strike plate in line with the 85 auxiliary bolt 54. The plunger 57 is normally protracted from the case of the switch mechanism in the ordinary manner, so as to extend into proximity to the head of bolt 54 when the latter is in the retracted position, 90 as shown in Fig. 2. When the bolt 54 is protracted by the mechanism hereinafter described, it pushes the plunger 57 into the casing of the switch mechanism, the construction of said mechanism being such that 95 when the plunger or button is so pressed in the electric circuit will be broken to turn out the lights in the room.

The auxiliary bolt 54 is adapted to be connected to and released from the main 100 locking bolt 22 by the following mechanism: In the head of bolt 54 is drilled a bore 58 in which is vertically slidable a locking pin 59. The bore 58 is open at the bottom of the auxiliary bolt so that the lower end of 105 the pin 59 is adapted to engage a socket 60 in the upper part of the main bolt head. When the parts are in the position shown in Fig. 1, the socket 60 registers with the lower end of bore 58 and a spring-pressed 110 lever 61 acting on the pin 59 presses it down into the socket 60 so as to lock the two bolt heads together, as shown in Fig. 8. The lever 61 is pivoted intermediate if its ends on a post 62 projecting forwardly from 115 the rear end portion of the shank 54^a of the auxiliary bolt, and said lever is acted on by a spring 63 which normally presses the forward end 64 of the lever in a downward direction. This forward end of the lever 120 engages a notch 65 in the pin 59 and consequently when it is forced downward by the spring 63 the pin engages the socket 60. The rear end of the lever 61 is bent backward, as shown at 66, and underlies an extension 46^c on the sweep 46^b of the secondary tumbler, as shown in Fig. 6. The bolt 54 is guided for reciprocating movement, 125 relatively to the main locking bolt, by means of the post 62, previously described, which 130

engages a slot 67 in an upwardly extending wall 68 on the bolt shank 29. When the post 62 is at the forward end of slot 67, the front end of the auxiliary bolt is flush with 5 the front end of the main locking bolt, and when the post is at the rear end of the slot, the auxiliary bolt is considerably retracted relatively to the main bolt. The lever 61 is laid flat against the shank 54^a of the 10 auxiliary bolt with its forward end extending through a slot 58^a into engagement with the locking pin in the bore 58, and the hole in the intermediate part of the lever fitting over the post 62, the outer face of 15 the lever being in contact with the inner face of the wall 68 and the extension 46^c being located at the rear of the shank 54^a. A screw 69, screwed into a threaded socket in the post 62, holds in place a clamping 20 plate 70 having an arm extending into engagement with the head of the auxiliary bolt and another arm extending into engagement with the fence 31 whereby the auxiliary bolt is held in the proper position 25 relatively to the main bolt.

The operation of the improved lock is substantially as follows: The normal position of the parts when the door is open is shown in Fig. 1. When the door is closed 30 from the inside by the thumb turn, the secondary tumbler is depressed and carried forward, in an obvious manner, carrying with it the slide 40, the bolt 22, and the primary tumbler. The auxiliary bolt, however, is not protracted, owing to the fact 35 that the actuation of the secondary tumbler by the thumb turn causes the extension 46^c to be depressed, thereby carrying downward the extension 66 on the rear end of the pin 40 operating lever 61 and raising the pin 59 out of the socket 60 and into engagement with the rear surface of the lock front. In other words, the auxiliary bolt is released 45 from the main bolt, and, at the same time, locked back in the casing, so that the main bolt is protracted alone. This main bolt has no coöperation with the light-controlling switch 55, and therefore the locking of the door from the inside has no effect on 50 the lighting circuit. When the guest leaves the room, however, and locks the door from the outside with the change key, the cam 34 is rotated individually so as to protract the bolt 22 with the primary tumbler, leaving 55 the slide 40 and the secondary tumbler in their normal positions, as shown in Fig. 4. As under these conditions there is no actuation of the secondary tumbler, the pin 59 remains in its normal position wherein 60 it locks the auxiliary bolt to the main bolt, and consequently both bolts are protracted simultaneously. As the head of the auxiliary bolt is in line with the plunger 57 of the switch, the latter is actuated to turn off 65 the lights, and thus when the key 48 locks

the door the lights are turned off automatically so that there will be no waste of current.

Supposing that the guest neglects to lock the door when he enters the room and the chambermaid, or someone else, locks the door from the outside, by one of the keys of lower order, which actuates the cam 34 individually, the guest can readily open the door by advancing the slide 40 and its connected tumbler mechanism from the position shown in Fig. 4 to that shown in Fig. 2, by giving the hub 24 a quarter-turn in a clockwise direction with respect to Fig. 4. Upon then reversing the direction of rotation of the thumb-turn hub, both bolts are then pulled back into the case. During the initial part of this movement, the pin 59 is thrust up out of the top of bore 58 in front of the face plate, but as the operation is continued a beveled surface 59^a, on the upper end of the pin, comes in contact with the upper edge of the opening in the face plate, thereby forcing down the pin to a position in which it permits the bolts to be retracted 90 without difficulty. When the door is locked from the outside by the emergency key both tumblers are actuated, but even in this case the guest cannot be locked in his room for the thumb turn will act on both tumblers 95 and retract the bolt 22, in the manner previously described.

Various changes may be made in the details of the construction without departing from the scope of the invention as defined in the claims.

What I claim is,

1. In a lock, two bolts, one of which is normally connected with the other, key actuated means for protracting both bolts by actuation of such other bolt, and thumb turn means for disconnecting said bolts from each other and protracting one independently of the other.
2. In a lock, two bolts, a pin normally connecting one bolt with the other, key mechanism for protracting both bolts simultaneously, and thumb turn mechanism for moving said pin to an inoperative position and protracting one bolt independently of the other.
3. In a lock, two bolts, one of said bolts being tumbler controlled, means for connecting the other bolt with and disconnecting it from said tumbler-controlled bolt, key mechanism for protracting both bolts simultaneously, and thumb turn mechanism for disconnecting said bolts and protracting one independently of the other.
4. In a lock, a tumbler-controlled bolt, a second bolt, means for connecting said second bolt with and disconnecting it from said tumbler-controlled bolt, means for protracting both bolts by actuation of said tumbler-controlled bolt, and means for disconnecting 125

the second bolt from the tumbler-controlled bolt and protracting the latter individually.

5. In a lock, a tumbler-controlled bolt, an auxiliary bolt, a pin normally connecting said auxiliary bolt with said tumbler-controlled bolt, means for protracting both bolts by actuation of said tumbler-controlled bolt when said pin is in the operative position, and means for disconnecting said pin and 10 protracting the tumbler-controlled bolt independently of said auxiliary bolt.

6. In a lock, a tumbler-controlled bolt, an auxiliary bolt, a pin normally connecting said auxiliary bolt with said tumbler-controlled bolt, means for protracting both bolts by actuation of said tumbler-controlled bolt when said pin is in the operative position, and means for disconnecting said pin and protracting the tumbler-controlled bolt independently of said auxiliary bolt, one of 15 said protracting means including a cylinder lock and the other protracting means including a thumb turn hub.

7. In a lock, a tumbler-controlled bolt, an auxiliary bolt, a pin normally connecting said auxiliary bolt with said tumbler-controlled bolt, means for protracting both bolts by actuation of said tumbler-controlled bolt when said pin is in the operative position, 20 and means for disconnecting said pin and protracting the tumbler-controlled bolt independently of said auxiliary bolt, said first protracting means including a cylinder lock and said second protracting means including 25 a thumb turn hub.

8. In a lock, two bolts, key mechanism for protracting said bolts simultaneously, and thumb turn mechanism for protracting one bolt independently of the other, but constructed and arranged to retract both bolts 30 when they have been protracted by said key mechanism.

9. In a lock, a tumbler-controlled bolt, an auxiliary bolt, means for connecting and disconnecting said bolts, means for protracting both bolts simultaneously, and means for protracting one bolt independently of the 35

other, said last-named means constructed and arranged to retract both bolts when they have been protracted by said first means. 50

10. In a lock, two bolts, a cylinder lock and change key for protracting both bolts simultaneously, thumb turn mechanism for protracting one bolt independently of the other, and means for retracting both bolts 55 by said thumb turn mechanism when they have been protracted by said change key.

11. In a lock, a tumbler-controlled bolt, an auxiliary bolt, means for connecting said auxiliary bolt with and disconnecting it 60 from said tumbler-controlled bolt, a cylinder lock, a change key for said cylinder lock adapted to protract both bolts simultaneously, thumb turn means constructed to disconnect said bolts and protract said tumbler-controlled bolt individually, and means for retracting both bolts by said thumb turn means when they have been protracted by 65 said change key.

12. In a lock, two bolts, means for connecting and disconnecting said bolts, means including a cylinder lock for protracting both bolts simultaneously, and thumb-turn mechanism for protracting one bolt independently of the other. 70

13. In a lock, two bolts, means normally interconnecting said bolts, means for protracting the bolts while they remain interconnected, and means for disconnecting the bolts and for protracting one of them individually. 75

14. In a lock, two bolts, means normally interconnecting said bolts so that they may be protracted simultaneously, key mechanism operative from the outside of the door 80 for so protracting said bolts, and thumb-turn mechanism operative from the inside of the door for disconnecting said bolts from each other and protracting one of them independently of the other. 90

In witness whereof, I have hereunto set my hand on the 10th day of April, 1917.

HENRY G. VOIGHT.
